UNITED STATES PATENT OFFICE.

HARRY F. BUSHONG, OF PORTLAND, OREGON, ASSIGNOR, BY MESNE ASSIGNMENTS, TO KALAMAZOO LOOSE LEAF BINDER COMPANY, A CORPORATION.

LOOSE-LEAF LEDGER.

No. 851,275.

Specification of Letters Patent.

Patented April 23, 1907.

Application filed July 15, 1904. Serial No. 216,664.

To all whom it may concern:

Be it known that I, HARRY F. BUSHONG, a citizen of the United States, and a resident of Portland, county of Multnomah, and State of Oregon, have invented a new and useful Improvement in Loose-Leaf Ledgers, of which the following is a specification, reference being had to the accompanying drawings as constituting a part thereof.

This invention has for its object to obtain a loose leaf book comprising two cover sections united by binding cords which are tightened and released again by suitable means to removably clamp the leaves bound between the covers, and having further a back strip which will be automatically adjusted by the adjustment of the clamping means, and the opening and closing of the book.

I accomplish my object by providing a transversely arranged bar, longitudinally movable in one of the cover sections to which bar the ends of the binding cords are secured, and by which bar such ends are tightened and released again to clamp the binding edges of the cover sections upon the bound leaves. I furthermore, provide a back strip, one or both ends of which telescope in a pocket or pockets therefor made on the exterior of the cover or covers and I connect one of said telescoping edges by bands, preferably elastic, with said adjustable bar so that the adjustment of said bar, and therewith the covers to the leaves inserted between the covers will simultaneously relatively adjust the back strip.

In the drawings, Figure 1, is a partial plan section of the exterior half of the two cover sections of my book, also showing means for tightening the binding cords and the described telescoping back strip and means for relatively adjusting the latter. Fig. 2 is a cross section on line $x-x$ of Fig. 1, with the interior parts removed. Fig. 3 is a detail perspective of the adjustable bar n .

In the drawings, similar letters of reference refer to similar parts throughout the several views.

The means for adjustably connecting the two cover-sections a, a' , in their general construction comprise a bar n , laterally adjustable in the cover section a' by a screw rod o , inserted in a bearing p and socket q , and binding cords h, h' , the extremities of which are fastened to the cover section a and the

bar n . The binding edges of the cover sections are provided with clamping jaws d, e , 55 pivoted in extensions b', c' , and through which clamping jaws the binding cords pass. The details of this part of the construction of my book are unimportant to this invention, however.

The material 3 covering the exterior of each of the cover sections is lapped across, to provide pockets 4 on the exterior of the cover sections in which are inserted and telescoped the ends of the back strip y . One of the ends of the back strip may be permanently fastened to the cover section a , if desired, and the other end alone telescope. But as shown both ends of the back strip telescope in the cover sections.

To hold the back strip in proper relation to the thickness of the leaves bound between the cover section and also to the opening and closing of the book, the end of the back strip y telescoping in the cover section a is fastened to the latter in a pocket 4 by means of elastic bands w, w . The opposite end of the back strip telescopes and is fastened in a like pocket 4 by means of elastic bands w', w' , to the adjustable bar n . To admit of such attachment, the wall 5 of the body of the cover section a' is made with longitudinal slots 2, 2, through which extend and in which slide the staples or other means fastening the bands w', w' , to the bar n . Of course, a single band would answer for attaching the ends of the back strip to the cover section a and the adjustable bar n , but two bands are preferred because distributing the pull more evenly. It is thus evident that the adjustment of the bar n to bind the inserted leaves will relatively adjust the back strip, and at the same time the latter is restrained by said elastic band-fastenings so as to be automatically arranged relatively to the opening and the closing of the book.

Having described my invention, what I claim and desire to secure by Letters Patent is:

1. The combination of the covers having 100 leaf clamping means thereon, and pockets opening at their inner end; binding cords connecting said covers; means for adjusting said binding cords carried by one of said covers; a back-strip arranged to telescope in 105 said pockets; connections for said back-

strip to said binding cord adjusting means and to the opposite cover, for the purpose specified.

2. The combination of the covers; binding cords connecting the same; an adjustable bar to the ends of which said binding cords are secured; means for adjusting said bar; pockets in the covers, a back-strip arranged to telescope within said pockets; and a connection for said back strip to said adjustable bar, for the purpose specified.

3. The combination of the covers; binding cords therefor; an adjustable bar carried by one of said covers, for tightening said

binding cords; means for adjusting said bar; 15 pockets in the exterior of the said covers; a back-strip arranged to telescope within said pockets; and connections for said back-strip to said adjustable bar, for the purpose specified.

20 In witness whereof I have hereunto affixed my signature in the presence of two witnesses:

HARRY F. BUSHONG.
